UNITED STATES PATENT OFFICE.

WILLIAM G. BUNTER, OF COAL CREEK, COLORADO, ASSIGNOR OF ONE-HALF TO
MICHELE FABRIZIO, OF COAL CREEK, COLORADO.

COMBINATION TACK-PULLER.

1,142,664.

Specification of Letters Patent. Patented June 8, 1915.

Application filed August 1, 1913. Serial No. 782,474.

To all whom it may concern:

Be it known that I, WILLIAM G. BUNTER, a citizen of the United States, residing at Coal Creek, in the county of Fremont and State of Colorado, have invented new and useful Improvements in Combination Tack-Pullers, of which the following is a specification.

This invention relates to combination tools and it consists in the novel features herein-after described and claimed.

An object of the invention is to provide a combination tool especially adapted to be used for pulling tacks, nails and so forth although the tool may be conveniently used as pliers and also as wire twisters and cutters.

The tool is provided at the ends of its handles with chisel extremities and wrench sockets of different dimensions and the tool is provided at the extremities of its jaw members with scraping edges adapted to be used for removing gaskets, washers, or the like from couplings or fittings and their seats.

With the above object in view the tool comprises two members pivotally connected together and being of the same general shape and configuration. These members are provided with jaw portions and handle portions, the extremities of the handle portions being provided with a chisel end and wrench sockets. The jaw portions are provided with beveled ends or extremities which may be used for scraping or cleaning the parts of boilers or machinery and the said jaw portions are further provided upon their inner sides with mated recesses, roughened surfaces and cutting edges as will be herein-after explained.

In the accompanying drawing:—Figure 1 is a perspective view of the tool. The other figures are detailed views of the several features thereof.

The tool comprises members 1 which are pivoted together as at 2. The said members consist of jaw portions 3 and handle portions 4. One of the handle portions 4 is provided with a chisel end 5 and the other handle portion 4 is provided with wrench sockets 6 of different dimensions.

As the jaw portions of the two members 1 are alike a description of one will answer.

Each jaw portion 3 is provided at its end and at its inner side with a beveled edge portion 7 and at its outer side with a beveled edge portion 8. The beveled edge portions 8 may be used for scraping.

The jaw portions 3 have angularly disposed end parts thereby providing humps at one side adapted to be used as a fulcrum when the tool is used. The bevels 7 are located at the opposite sides of the jaw portions 3 from the said humps.

Just within the beveled edge portion 7 each jaw portion 3 is provided with a transversely disposed groove 9 and just within the said groove each jaw portion is provided with a flat surface 10.

At the inner edge of the surface 10 is located a transversely disposed groove 11 and a roughened surface 12 is located adjacent the groove 11.

At the inner edge of the roughened surface 12 is located a recess 13 having at its lower end a cutting edge 14. The grooves and surfaces of the two jaw portions 3 mate with each other and when the said jaw portions are closed together the said groove and surfaces register with each other. The jaw portions 3 are curved longitudinally out of alignment with the long dimensions of the handle portions 4. Thus when the beveled portions 7 are brought together they may pass under the head of a tack and by swinging the handle portions 4 in a downward direction the tack may be lifted out of the material in which it is located. Should the tack have an unusually long shank the tack may be started as above indicated and then the shank of the tack can be received in the grooves 9 and the tack lifted out of the material in which it is located.

For removing nails the grooves 11 are placed about the opposite sides of the same and the surfaces 10 may be used for holding flat objects. The roughened surfaces 12 may be used for twisting wire or like objects and the cutting edges 14 may be used for cutting wire, nails and similar articles. Therefore it will be seen that a combination tool of simple structure is provided.

Having described the invention what is claimed is:—

A tool comprising members pivotally connected together said members having han-

dle portions and jaw portions provided with humps located at one side, the jaw portions being provided at their forward ends and at their inner portions and at their sides opposite the said humps with inwardly and forwardly beveled surfaces terminating in edges at the ends and inner portions of the said jaws.

In testimony whereof I affix my signature in presence of witnesses.

WILLIAM G. BUNTER.
